BUCKLE

Original Filed June 24, 1931

UNITED STATES PATENT OFFICE

HENRY ST. PIERRE, OF WORCESTER, MASSACHUSETTS

BUCKLE

Application filed June 24, 1931, Serial No. 546,459. Renewed October 7, 1931.

This invention relates to a holding device for a strap and is particularly adapted for use on a strap for a cross chain or mud hook for an automobile tire.

5 The principal objects of the invention are to reduce the buckle or holding device to its simplest terms and to make it of a single sheet of metal, preferably flat, requiring no machine work and affording all the holding surfaces necessary to secure the strap to it and 10 distribute the strain among a plurality of surfaces.

Other objects and advantages of the invention will appear hereinafter.

15 Reference is to be had to the accompanying drawings, in which

Fig. 1 is a plan of a single mud hook and buckle constructed in accordance with this invention;

20 Fig. 2 is a plan of the buckle by itself; Fig. 3 is an edge view thereof;

Fig. 4 is a view like Fig. 1 showing the invention applied to a double mud hook, and

25 Fig. 5 is a plan of the buckle modified for connection with two chains, being the same as that shown in Fig. 4.

In Figs. 1, 2 and 3 I have shown this invention in its simplest form suitable for holding a single chain 10 of a mud hook or the 30 like, this chain having a fastening buckle 11 on one end and a hook 12 on the other.

The buckle 13 itself is formed of a piece of sheet metal made flat and plain. It has a loop portion 14 around it at one end into 35 which the bent ends of the hook 12 are adapted to engage as shown in Fig. 1. At the other end it has a straight bar 15 and it has two intermediate bars 16 and 17, all extending all the way across the buckle.

40 The canvas or other flexible strap 18 to be held by it is passed upwardly through the space between the bars 15 and 16 over the bar 15 and then downwardly and all the way around the bar 17 and back over the bars 17 and 16 respectively and then down over the strand previously described, and in contact with the bar 15. The end of the strap is permanently secured to the strap itself at a point 45 beyond the bar 15 by means of a rivet 19 or the like, near the end bar. This furnishes a

very strong holding means in which the friction of the textile material, of which the strap is made, is exerted between two layers thereof over a bar 16 to distribute the strain.

55 In use, this part of the device is held, of course, in as flat a condition as possible so that the bar 15 is forced down against the upper layer of the strap to add to the frictional resistance against any abnormal pull on the rivet. The surrounding of the bar 17 by the 60 strap adds still further to the resisting influence so that this single rivet will hold the strap under a very heavy pull and rough usage. There is no danger of its becoming 65 loosened and some of the resistance above mentioned lost because there is no position for the parts of the strap to assume under strain except the one illustrated and described.

70 Substantially the same conditions apply when this article is used for a double chain construction as shown in Figs. 4 and 5. Here the loop 14 is eliminated but two eyes 20 are used, forming a part of the body 21 of the buckle. The bars 15, 16 and 17 are in the 75 same position as in the other figures and perform exactly the same functions. The locking or binding buckles 11 and 22 are not described in detail as they do not constitute a part of this invention.

80 Although I have illustrated and described only two forms of the invention I am aware of the fact that other modifications can be made therein by any person skilled in the art without departing from the scope of the invention as expressed in the claims. Therefore I do not wish to be limited in this respect but what I do claim is:—

85 1. As an article of manufacture, a flat plain buckle for holding the end of a strap comprising a straight bar at the end and two intermediate bars, each extending all the way across the buckle and means carried by the buckle for securing a mud hook thereto, the body of the buckle extending outwardly at both sides and having a pair of eyes oppositely offset from the bars for receiving two chains.

90 2. As an article of manufacture, a buckle having three bars for holding the end of a

strap, the buckle extending outwardly at both sides and having opposite attaching means on said extensions.

3. As an article of manufacture, a buckle for holding the end of a strap comprising three parallel bars, each extending all the way across the buckle, the body of the buckle extending outwardly at both sides and having a pair of attaching means oppositely offset from the bars.

10 In testimony whereof I have hereunto affixed my signature.

HENRY ST. PIERRE.
